UNITED STATES PATENT OFFICE.

JOHN I. MARSHALL, OF BOSTON, MASSACHUSETTS.

DESIGN FOR A HOLLOW TILE FOR BAKE-OVENs.

SPECIFICATION forming part of Design No. 32,136, dated January 23, 1900.

Application filed December 15, 1899. Serial No. 740,476. Term of patent 14 years.

To all whom it may concern:

Be it known that I, JOHN I. MARSHALL, a citizen of the United States, residing at Boston, in the county of Suffolk and State of Massachusetts, have invented and produced a new and original Design for Hollow Tiles for Bake-Ovens, of which the following is a specification, reference being had to the accompanying drawing, forming a part thereof.

In the drawing I show a perspective view of the tile.

As shown in the drawing, the tile is oblong rectangular in form and apertured from end to end. Each side wall has a longitudinal channel. One of the broad faces of the tile, which may be called the "top" thereof, is of less width than the opposite face, so that the two portions of each side wall upon opposite sides of its channel are in different planes. The top wall of the tile is of greater thickness than the bottom wall, and along each upper interior corner there is a fillet extending downwardly below the line of the external channel in the side wall.

I have thus far described the leading and material features of the design, all of which I have shown in solid lines. The minor and less important feature of the design is a central longitudinal vertical partition - wall shown in dotted lines and separating the chamber of the tile into two compartments.

Having described my design, what I claim as new, and desire to secure by Letters Patent, is—

The design for a hollow tile for bake-ovens, as herein shown and described.

In testimony whereof I have signed my name to this specification in the presence of two subscribing witnesses.

JOHN I. MARSHALL.
